SKI FITTING

Jakob Eigenheer, Thalwil, Switzerland, assignor
to the firm Belmag Zurich, Beleuchtungs- &
Metallindustrie Aktiengesellschaft, Zurich,
Switzerland, a joint-stock company of Switzerland

Application April 22, 1943, Serial No. 484,050
In Switzerland March 28, 1942

6 Claims. (Cl. 280—11.35)

Object of this invention is a ski fitting. Ski fittings with a pull member encircling the heel of the rider and with a tightener to tighten the pull member for holding the boots against the toe holding irons of the skis are already known. In these devices, either a spring encircling the heel of the boots is inserted into the pull member, or a resilient means arranged between tightener and pull member in the fore part of the fitting. These constructions merely allow of a fine adjustment, that is, the correction of alternations caused by skiing either on the boots or on the pull member. This adjustment could only amount to some millimetres so that it was necessary either to have several pull organs of different lengths or to shorten the pull member when mounting, which shortening, however, could only be carried out by men skilled in the art. A standard fitting with adjusting possibilities allowing of an adaptation to any size boots in question was lacking.

The ski fitting according to the invention remedies these inconveniences. It comprises a pull member encircling the heel of the rider, ends of which are fixed to a fore pulling device. An adjusting screw connects the pull member with the tightener.

By preference, the adjusting screw may be provided in the interior of a tension spring arranged between the webs of a tightener of U-shaped cross section. The head of the adjusting screw may be pivoted on the tightener or, on the contrary, the spring, with its one end, may be pivoted on the tightener and carry a nut on its other end which engages the adjusting screw. In a preferred embodiment the two ends of the pull member may be attached to a connecting piece whose symmetry plane is inclined with regard to the axis of the adjusting screw; the advantages resulting therefrom will be shown later on.

The accompanying drawings illustrate, by way of examples, various embodiments of the ski fitting according to the invention, of which only those parts are shown and described relating to the invention.

Fig. 1 is an upright projection, and

Fig. 2 a top view of a first embodiment,

Fig. 3 is an elevation of a second and

Fig. 4 of a third embodiment,

Fig. 5 is an upright projection and

Fig. 6 a plan view of a fourth example and

Figs. 7 and 8 show an elevation and a top view of a fifth form of performance.

Referring to Figs. 1 and 2 the pull member in the form of a cable 1 encircles in a non-illus-

trated manner the heel of the rider and has at the ends members 2 each located in a tube 4 of a connecting piece 3. Over a certain length these tubes 4 are provided with inside threads engaging a hollow nut 5 through which the cable 1 passes. By means of these screws a fine adjustment of the cable length becomes possible.

The connecting piece 3, which may either be pressed in two parts or cast, carries a head 6 which is threaded into the one end of a spring 7 thus fixing the piece 3 with the cable 1 to this spring. A nut 8 is threaded into the other end of the spring 7, engaging an adjusting screw 9 whose head is pivoted on a lever 11 by means of the pin 10. This lever is U-shaped and pivots 12 are mounted on its webs which engage the teeth 13 of a lug 14 screwed to the ski.

From Fig. 1 it may be seen that the median plane X—X of the connecting piece 3 is inclined with regard to the axis y—y of the spring 7 and screw 9, so that two different positions can be given to the connecting piece and thereby to the cable so that, when placing the boot on the ski, one can install the cable for a diagonal or horizontal pull.

When the lever 11, with the parts connected to it, is attached to the lug 14 by means of the pivots 12 and the teeth 13, the nut 8 can be displaced along the screw 9 by rotating the cable, the connecting piece and the spring 7. In this way the length between the pin 10 and the heel of the rider can be adjusted up to a degree which only depends on the length of the screw. The latter can be made very long, e. g., almost as long as the spring 7 so that the coarse adjustment possible in this way (e. g., 1 to 6 cm.), is sufficient to adapt, at any previously adjusted position of the pivot 12 on the teeth 13, the ski fitting to any practically existing size of boots.

Forming the tightener as a U-shaped lever and placing the spring with the adjusting screw in the interior of this lever represents, besides the small weight and great moment of resistance, the further advantage of a simple construction and a very small space required.

In Fig. 3 only the lug 14 is modified with regard to the embodiment shown in Figs. 1 and 2. Here the teeth 13 are not provided on openings of the ears of the lug but on the upper border 50 of these ears, allowing of an easy removal of the whole harness from the ski before transporting the latter. Taking away the harness from the ski is also a good safety measure against theft of the snow shoes.

The ski fitting shown in Fig. 4 resembles the

one in Fig. 3 so that similar letters of reference indicate corresponding parts. However, in Fig. 4 the adjusting screw 9 is fixed to the connecting piece 3 by means of a pin 24 going through the head 25 of the screw and through the two parts of the connecting piece made of pressed sheet metal. At the other end of the spring 7 a head 26 is threaded into the spring which is pivoted to the lever 11 by means of the pin 10. The ears of the lug might also be formed as those shown in Fig. 1, that is, the teeth might be provided on an opening of the ears.

In Figs. 5 and 6 the screw 9 is, as in Fig. 4, attached to the connecting piece 3. However, at the right-hand end the spring has a hook 15 engaging a loop 16 pivoted on both its sides on the tightener 17 by means of a pin 18. Lever 17 is pivoted on the lug or bracket 20 by means of the pin 19. Here, the possibility of adjusting the tightening lever in teeth, as shown in the previous embodiments is lacking, it might, however, be provided. Any adjustment of the pulling device takes place by rotating cable 1 and connecting piece 3, displacing in this way the screw 9 in the nut 8.

The device illustrated in Figs. 7 and 8 resembles the one shown in Figs. 1 and 2. However, the lug 14 screwed to the ski is shaped in such a way that the pivots 12 can be taken out of the lug 14 without being dismounted from the lever 11. For this purpose the ears of the lug 14, on the right of the hindmost tooth 13 are formed as a guide 22 through which the pivots 12, flattened for this purpose on two opposite sides, can pass to the outside. In this way the advantages of the lugs 14 of Figs. 1 and 3 are combined.

What I claim is:

1. In a ski fitting, a connecting piece, a pull member connected to said connecting piece, a lug, a tightener of U-shaped cross section, pivoted on said lug, and a connection device between said tightener and said connecting piece, comprising a tension spring lying between the webs of said U-shaped tightener, and an adjusting screw rotatable relatively to said tension spring.
2. In a ski fitting, a connecting piece, a pull member connected to said connecting piece, a

lug, a tightener of U-shaped cross section, pivoted on said lug, and a connection device between said tightener and said connecting piece, comprising a tension spring lying between the webs of said U-shaped tightener, and an adjusting screw pivoted to the webs of said U-shaped tightener and rotatably connected with said tension spring.

5 3. In a ski fitting, a connecting piece, a pull member connected to said connecting piece, a lug, a tightener of U-shaped cross section, pivoted on said lug, and a connection device between said tightener and said connecting piece, comprising a tension spring pivoted to the webs of said U-shaped tightener and provided with a nut, and an adjusting screw fixed to said connecting piece and engaging said nut.

10 4. In a ski fitting, a connecting piece having a symmetry plane, a pull member connected to said connecting piece, a lug, a tightener of U-shaped cross section, pivoted on said lug, and a connection device between said tightener and said connecting piece, comprising a tension spring lying between the webs of said U-shaped tightener, and an adjusting screw and engaging said nut.

15 20 5. In a ski fitting, a connecting piece, a pull member connected to said connecting piece, a lug, a tightener of U-shaped cross section, pivoted on said lug, and a connection device between said tightener and said connecting piece, comprising a tension spring lying between the webs of said U-shaped tightener, and an adjusting screw rotatable with regard to said tension spring and the symmetry plane of the connecting piece being inclined with regard to the axis of the adjusting screw.

25 6. In a ski fitting, a connecting piece, a pull member connected to said connecting piece, a lug, a tightener of U-shaped cross section, pivoted on said lug, and a connection device between said tightener and said connecting piece, comprising a tension spring lying between the webs of said U-shaped tightener, and an adjusting screw rotatable with regard to said tension spring.

30 7. In a ski fitting, a connecting piece, a pull member connected to said connecting piece, a lug, a tightener of U-shaped cross section, pivoted on said lug, and a connection device between said tightener and said connecting piece, comprising a tension spring lying between the webs of said U-shaped tightener, and an adjusting screw rotatable with regard to said tension spring.

JAKOB EIGENHEER.
